[57] **CLAIM**

The ornamental design for a mitre box, as shown.

DESCRIPTION

FIG. 1 is a perspective view of a mitre box showing our new design with the saw guide assembly in one rotated position;

FIG. 2 is a front elevational view with the saw guide assembly pivoted into a right angular position;

FIG. 3 is a rear elevational view thereof;

FIG. 4 is a plan view thereof;

FIG. 5 is a bottom view thereof;

FIG. 6 is an end elevational view thereof; and

FIG. 7 is an elevational view of the opposite end thereof.

FIG. 1

FIG.2

FIG. 3

FIG. 4
